UNITED STATES PATENT OFFICE

2,347,283

MEANS FOR DRESSING GRINDING WHEELS

Walter F. Ross, Detroit, Mich.

Original application October 30, 1939, Serial No. 301,918, now Patent No. 2,307,238, dated January 3, 1943. Divided and this application June 3, 1940, Serial No. 338,492

2 Claims. (Cl. 125—11)

This invention relates to apparatus for the dressing of grinding wheels for the finish forming of gear teeth, lobes or similar forms, and to the method of producing the form of abrasive wheel; this application being a division of my co-pending application, Serial No. 301,918, filed October 30, 1939, which matured as Patent No. 2,307,238, January 3, 1943. The said invention has for its object to provide for the production of a form of grinding wheel which will lend itself to the finish forming of gear teeth, and so forth; in such manner that gears or forms of great perfection and tooth or formed surface fidelity, both as to contour and spacing, may be produced, such gears and forms as a result having a correspondingly higher degree of practical strength with noiseless operation, and being capable of production practically without restriction as to tooth or other form.

An important object of the said invention is to provide a main grinding wheel having a thread formed thereon in such a manner that the section of the wheel face taken normal to the helix is the conjugate of the normal pitch of the gear being ground and which is accurate and specifically adapted to the contour of each specific size, style, and space of tooth; and which is further adapted to progressively grind the full form of each tooth simultaneously on both sides around the gear in continuous cutting relation thereto, without the indexing which is usually called for.

A further important object is to provide for the reduced reproduction of an enlarged pattern of the required conjugate rack tooth space section by steps which include the dressing of the said form of tooth section, by pantograph control on a dresser wheel, and the recessing of such form by said dresser wheel in the surface of the grinding wheel as a helix having the normal pitch of the normal pitch of the teeth to be ground in the work. The invention also contemplates formation of such helical grinding wheel with a face width of some whole multiple of the helix lead as a means of insuring running balance.

Still further objects or advantages subsidiary to result from the aforesaid objects, or from the construction or operation of the invention as it may be carried into effect, will become apparent as the said invention is hereinafter further disclosed.

In carrying the said invention into effect, I may provide a gear or form grinding machine comprising, in general, a large rectangular base structure having mounted on the center portion a main grinding wheel characterized by its being provided

with a helical thread of a cross section at right angles to the lead thereof which is the conjugate rack of the normal pitch of the gear to be ground; and in advance of said grinding wheel a dresser wheel driven by a small motor mounted for adjustment to angular positions about a horizontal axis at right angles through the axis of rotation of the dresser wheel, whereby said dresser wheel may be set at an angle equivalent to the helix angle to be dressed on the main grinding wheel.

Suitable mechanism is provided to effect the movement of the dressing wheel in a direction parallel to the axis of the main grinding wheel to adjustable limits in either direction, and to effect its movement into and out of working position relative to the said main grinding wheel at opposite ends of its working travel, much in the manner of the action of a threading tool when used in a lathe. Means for progressively feeding the dresser wheel into the grinding wheel to promote the dressing cut are also provided.

For the formation of the required contour of the margin of the dressing wheel in order that it may produce the proper helix section on the main grinding wheel, I may provide on the forward end of the machine a pantograph mechanism adapted to translate the template-controlled motion of a tracer disc into reduced motion of a dressing diamond which may be moved up to the aforementioned dresser wheel to effect its dressing, the diamond being accurately lapped and polished, in so far as its active edge is concerned, to a circular cross section whose diameter is a fraction (say, one-tenth) of that of the tracer disc.

A template having the form of the rack tooth space to be ground by the main grinding wheel, and in the same proportion as the tracer disc is to the diamond (say, 10 times the section) is suitably mounted on the machine for guidance of the tracer disc during the operation of dressing the dresser wheel by the said diamond.

In carrying the said invention into effect, I may utilize the novel construction and arrangement of parts hereinafter described, by way of example, having reference to the accompanying drawings, wherein:

Figure 1 is a front end elevation of a machine embodying the said invention.

Figure 2 is a plan of the same.

Figure 3 is a side elevation of the same.

Figure 4 is a vertical section of the same taken on a plane indicated by the line 4—4 in Figure 2.

Figure 5 is a horizontal section of the same taken on a plane indicated by the line 5—5 in Figure 4.

Figure 6 is a detail sectional view illustrating the adjustable mounting of the dresser wheel feed screw.

Figure 7 is a horizontal section of the machine taken on a plane indicated by the line 7-7 in Figure 4.

Figure 8 is a diagram illustrating the pantograph linkage associated with the form templet.

Figure 9 illustrates in larger scale detail and in plan the abrading wheel shown in association with the dressing wheel and also in association with a gear to be finish formed; and

Figure 10 is a detail front elevation of the elements shown in Figure 9.

Similar characters of reference indicate similar parts in the several figures of the drawings. Certain supporting structure which would interfere with a clear illustration of the mechanism and which is not necessary to an understanding thereof is eliminated from some of the sectional illustrations of the drawings. 15 20

The machine, as illustrated, is part of a complete machine for the finish forming of gears and so forth, more extensively described in my co-pending application, Serial No. 301,918, filed October 30, 1939, the description and illustration in this application being confined to that mechanism associated with the dressing and operation of the abrading wheel and comprises a base structure 20 housing a dresser feed mechanism, which will be later described, and supporting the main abrasive grinding wheel 21, the spindle 22 of which is rotatively carried by a slide 23 parallel thereto and adjustable transversely of the machine in ways 24 by a manual feed screw 25.

Positioned on the machine in advance of the main grinding wheel 21 is a dresser wheel 26 mounted on the spindle 27 of a motor 28, which motor is carried by an arcuate member 29 for swinging movement about the center of the dresser wheel 26 by virtue of its being rotatable in arcuate ways 30 of a quadrant support 31. Also carried by the motor support member 29 is a pantograph table 32, movable on the said member 29 towards and from the dresser wheel 26 by means of the manually operable adjusting shaft 33 through the medium of gears 34 and 35 and of the feed screw 36.

and of the feed screw 30. The quadrant support 31 and the previously described elements mounted thereon is movable longitudinally and transversely of the machine by reason of its being in turn provided with a saddle 37 adjustable lengthwise of the machine on the slide 39 by means of the manual adjusting screw 38. The said slide member 39 is also carried by a saddle 40 transversely movable of the machine on a cross slide 41 under the influence of a feed screw 42 engaging in a nut 43 on the underside of the said saddle 40, which means of operating the said feed screw 42 being later referred to.

The cross slide 41 is also capable of reciprocation in the direction of the length of the machine by virtue of its being mounted on the longitudinally slidable member 44 which receives its motion from a pinion 45 engaging a rack 46 on the underside of the said slidable member 44, as best seen in Figure 5, the source of operation of the said pinion 45 being also referred to in detail hereinafter.

From the foregoing arrangement of slides, it will be seen that provision is made whereby the dresser wheel 26 and the main abrasive grinding wheel 21 are movable relative to each other in practically all directions, and in the illustrated

example, all of these adjustments and movements are for convenience associated with the said dresser wheel 26, the main grinding wheel 21 in this case being non-adjustably mounted on the machine, except insofar as the manual cross feed by the said screw 25 is concerned. This cross feed of the main grinding wheel 21 does not, however, have any bearing on the relationship with the dresser wheel 26 and is simply used on occasion in connection with the the grinding of work in the machine by the said main abrasive grinding wheel.

The said main grinding wheel 21 is intended to be driven at a high speed in one direction when performing its gear grinding operation and receiving its power from the main motor 47, but when the thread is being formed on the main grinding wheel 21 by the dresser wheel 26 it is driven in alternately changing directions at low speed receiving its power from a smaller auxiliary motor 48 which is shown in this case as being situated exterior to the base structure of the machine; the selection of the drive to the main grinding wheel being controlled by a manually operable clutch according to requirements.

When the said main grinding wheel 21 is being driven for the grinding of work, it receives its power from the main motor 47 through the medium of Reeves gear 49, main pulley 50, belt 51, pulley 52 and clutch member 53 which rotates with the shaft 54 and is moved into engagement with the said pulley 52 by means of a clutch operating rod 55 under the influence of the clutch handle 56 by suitable belt crank linkage (not shown). Said shaft 54 in turn transmits the power through the pulley 57 and belt 58 to the large pulley 59 of the main grinding wheel spindle 22.

60 is the Reeves gear control and wheel which, through the shafts 61, 62 and 63, suitably geared together, controls the regulation of the said Reeves gear, in the manner well known, to increase or diminish the speed of the main grinding wheel within reasonable limitations to suit varying degrees of wheel hardness or abrasive quality, or to meet variable grinding conditions such as differing gear hardness, and so forth.

Nominally it is proposed to proportion the pulleys and the motor speed of 3600 R. P. M. and a grinding wheel spindle speed of 1800 R. P. M. although, of course, grinding wheel spindle speed beyond that permitted by regulation of the Reeves gear, may be simply effected by varying relative sizes of the pulleys 57 and 59.

The main grinding wheel 21 which it is proposed to use in the finish forming of gear teeth through the agency of suitably timed mechanism (not shown) operating the work 64, is intended to have a characteristic helical thread formed thereon which in section transverse of the lead angle is the conjugate rack for the gear or work to be ground considered in relation to the normal pitch of such gear; and in producing the said form on the said main grinding wheel 21 it is preferably first rough chased on an engine lathe in relation to certain key ways (not shown) in the wheel hub in order to save time in the dressing operation about to be described.

The dressing operation is effected by the dresser wheel 26 in the form of a disk of emery or the like, having its marginal portion formed in cross section as the reverse or counterpart of the spacing of the conjugate rack of the gear to be ground. This cross sectional form of the margin of the dressing wheel 26 it is proposed to produce by

the pantograph mechanism which will be later described.

After the rough chased grinding wheel 21 has been mounted on the grinding wheel spindle 22, the clutch 53 is moved towards the left of the machine to engage a clutch member 65 in which position the said clutch 53 is released from the main drive counter-shaft pulley 52 and now couples the shaft 54 (and consequently the grinding wheel spindle 22) with the low speed shaft 66. This shaft 66 through gear 67, 68, shaft 69, gears 70 and 71, shaft 72 and gears 73 and 74, is driven in one or other direction by a bevel gear 75 and obtains its rotation from one or other of bevel pinions 76 and 77, either of which pinions may be coupled to a drive shaft 78 by a sliding dog clutch 79 keyed to the said shaft 78.

The clutch 79 is actuated by a clutch shifting member 80 located between compression springs 81 and 82 and is slidable on the rod 83, in one or other direction as one or other of the said compression springs is loaded beyond a determined degree, a system common in load and trip mechanisms. 84 is a spring loading fork the arms of which travel on the said rod 83 and are intended to alternately depress the said springs 81 and 82 under the influence of a reciprocating bar 85 connected to the lower end of a lever 86 pivoted at 87.

The shaft 78, operating the forward and reverse pinions 76 and 77, receives its power from the auxiliary motor 48 through the shaft 88 and worm and worm wheel 89 and 90. Thus, during the dressing of the said main grinding wheel 21 by the dresser wheel 26, the said main grinding wheel 21 is rotated at relatively slow speed alternatively in opposite directions and is driven by the said auxiliary motor 48. The said dresser wheel 26 is driven independently by its own high speed motor 28.

By adjusting the angle of the arcuate member 29 of the dresser wheel motor mounting, the plane of the dresser wheel 26 may be set to the helix angle which it is desired to form on the main grinding wheel 21, which is governed by the normal pitch as related to the diameter of the wheel 21, and which has preferably been already roughed out on an engine lathe as stated; and by means of the manual dresser wheel feed screw 38, the said dresser wheel 26 is moved up into dressing position in the roughed-out groove of the grinding wheel 21. The dresser wheel 26 and the grinding wheel 21 being then rotated by the motor 28 and 48, respectively, in the accepted relative directions for efficient dressing of the grinding wheel 21, the said dresser wheel 26 is given a motion similar to that of a threading tool when used in a lathe, the dresser wheel 26 traversing the main grinding wheel face at a controlled rate of travel to generate in the walls of the roughed-out groove the desired thread formation, dropping back at the end of the travel to clear the grinding wheel face, then returning to its starting point and being advanced to its pre-determined dressing position, following which the dresser wheel 26 again traverses the wheel face, and so on, until the cycle is stopped by the operator. It will be understood that as the cycle is repeated, the dresser wheel 26 is progressively advanced into the work, as required, by operation of the said dresser wheel feed screw 38.

This lath like action of the dresser wheel 26 is secured by throwing the clutch 91 into position where it is disconnected from the shaft 92 (which

shaft 92 bar is directed through gears 93 and shaft 94 to such mechanism as may be provided for controlling the operation of the work 64) and connects the shaft 95 through its bevel gears with the shaft 96 operated from the grinding wheel spindle 22, which shaft 95 through gears 97 and 98, shaft 99 and change gears 100, 101, 102, and 103, operates the dresser travel feed shaft 105 to the inner socket end 106 of which the squared extension 107 of the dresser travel feed screw 42 reciprocally engages. This feed screw 42 is manually adjustable axially of the feed shaft 105 by means of an adjusting screw 108 independently rotatable on an extension spindle 109 of the said feed screw 42 and threaded into one end of the slide 41, whereby rotation of the said adjusting screw 108 will effect longitudinal movement as a whole of the feed screw 42. This effects corresponding adjustment of the dresser wheel 26 crosswise of the machine by virtue of the said wheel 26 being movable with the slide 40 coupled to the said feed screw 42 by the nut 43. Thus the operation of the said manual adjusting screw 108 serves to determine the lateral adjustment of the dresser wheel 26 to the roughed-out groove of the main grinding wheel 21 with which the said dresser wheel 26 is to match. To effect such matching the main grinding wheel cross feed screw 25 may also be utilized, if desired.

When the dresser wheel travel feed screw 42 is rotated in one or other direction, the nut 43 travels along the said feed screw 42 until an extension 110 on the said nut 43 strikes the inner end of one or other of stops 111 or 112 which stops are threaded for adjustment into sleeves 113 and 114 slidably movable in the slide 41 and connected to the opposite ends of a link 115 attached to the upper end of the pivoted lever 86. Such contact of the nut extension 110 with the stop 111 or 112, as the dresser wheel 26 completes its forward travel, or its return stroke, causes the said lever 86 to swing in one or other direction about its pivot 87 and, through the connecting rod 85 and fork 84, snap the reverse clutch 79 out of engagement with one of the pinions 76 or 77 and into engagement with the other of said pinions. In this manner the direction of rotation of the main grinding wheel spindle 22 as well as the direction of rotation of the grinding wheel travel feed screw 42 is reversed.

As the lateral working travel of the dresser wheel 26 is completed in grinding the groove in the main grinding wheel 21, as described, and the connecting rod 85 is operated to reverse the motions and effect the return of the dresser wheel 26 to the beginning of its stroke, it is desirable to withdraw the dresser wheel 26 from the work prior to such return stroke. This may be effected by any suitable mechanism and for the purposes of illustration the connecting rod 85 is shown as being provided with an arm 116 connected by a rod 117 to a cam plate 118 mounted for longitudinal movement by the said rod 117. The lobes 119 of the said cam plate 118 are arranged to effect the movement of a plate 120 at right angles to the movement of the said cam plate 118, as will be readily understood, and, as this plate 120 is connected to the end of a swinging arm 121 on the lower end of the shaft 122 carrying the pinion 45, it will be apparent that such movement of the said plate 120 will result in the rotation of the said pinion 45 in one or other direction according to the direction of movement of the said plate 120. The lobes of the cam plate 118 are intended to be so disposed that through the link-

age described and the said pinion 45 they will effect the motion of the rack 46 and the dresser wheel carrying slide 44 to withdraw the dresser wheel 26 from the work as required at the end of each working stroke, and also to advance the wheel 26 to the said work prior to the beginning of each working stroke.

It will be understood that when any major reduction of the diameter of the main grinding wheel 21 is made, the normal pitch of the thread being maintained, the lead angle and the actual lead increases in a definite proportion which can be readily calculated, so that the change gears 100, 101, 102, and 103 or their equivalent are intended to be correspondingly selected or operated to produce the required proportional feed of the feed shaft 42. Therefore, this feed will be determined by the normal pitch form of the dresser wheel and the angularity to which it is set.

Figures 9 and 10 show more particularly, the relationship of the dresser wheel 26, the main grinding wheel 21 and the work 64, and it will be noted that the main grinding wheel is characterized by a formed helical thread 140 having a pitch measured at right angles to the lead of the thread, as distinguished from the usual method of measuring the pitch of a screw on a line parallel to its axis. In the example, this pitch is that of the normal pitch of the teeth 141 to be ground on the said gear 64. (The gear in this case being a spur gear, the normal pitch is also that of the circular pitch, but in the case of a helical gear, such would not be the case, as is well recognized in the art.)

I am aware that it has been in the past broadly and vaguely suggested that an abrasive wheel with a helical grinding thread thereon might be used for the purpose of grinding gear teeth and, where extreme accuracy is of secondary importance, such a wheel might be so employed, but it has been generally assumed that the thread on the abrasive wheel might be produced or formed by a cutter travelling parallel to the axis of the wheel as in the ordinary screw threading process, or by means of dressing disks rotating in a plane transverse of that of the abrading wheel. Further, it has been suggested to utilize an abrading wheel having its thread produced by flat-faced dressing disks extremely limited as to the forms of thread they are able to produce.

The thread form of my abrasive wheel 21 is however that produced by the dresser wheel 26, the marginal portions 142 of which has sides which are the counterpart of the conjugate rack of the tooth to be ground on the work, the said dresser wheel 21 being presented to the abrasive wheel in a plane corresponding to the lead angle of the thread being formed on a dresser wheel. This produces a groove which is the true counterpart of the cross sectional form of the dresser wheel periphery when this contour of the groove is viewed in a plane at right angles to the lead as distinguished from a plane coincident with the axis of the abrasive wheel. Consequently the resulting form of tooth which such abrasive wheel may produce on the gear or work is directly conjugate to the thread form of the periphery of the dresser wheel, which would not be the case were the dresser wheel presented to the abrasive wheel at right angles to the axis thereof and consequently at an angle to the lead.

It, therefore, follows that any abrasive wheel of this general thread type which is produced by a conjugate rack form tool of any type presented to the abrasive wheel other than at an angle con-

forming to the lead, would not comply with the thread form herein described.

My abrasive wheel is thus characterized by a helicoidal rack generated on the surface of an abrasive cylinder, and having a cross section taken normal to the thread which is the conjugate rack section of the gear form in a plane normal to the gear teeth to be produced.

In Figure 10, the line *a* indicates the angle to which the axis of the dresser wheel is tilted relative to the direction of feed indicated by the line *b* to produce the thread form shown on the abrasive wheel 10, and the line *c* indicates the plane at right angles to the normal pitch of the gear 13 which, in this case being a spur gear, happens also to be the circular pitch of the gear.

Of course, it will be understood that this abrasive wheel readily lends itself to precise modification as to thread section to meet modifications as to tooth form required in the finished work.

The described abrasive wheel especially lends itself to the form finishing after hardening of helical gears which heretofore, due to present methods of work, have involved considerable expense in determining the extent to which such helical teeth tend to straighten out as a result of the hardening process, and it has been common practice to make such helical gears with the teeth initially of greater angle than the final angle to be attained, this very often entailing highly expensive cut-and-try operations with simple gears before the satisfactory result for any particular gear could be obtained. The use of applicant's improved abrading wheel as the implement for form finishing such gears after hardening renders unnecessary this expensive and time-consuming preliminary experimental work.

Means are provided for dressing the contour of the counterpart of the conjugate rack form dresser wheel 26 to that of the rack to be eventually ground on the main grinding wheel 21, such means including the well-known pantograph motion, the principle of which does not need to be dwelt upon at length; 123 and 124 being the parallel links connecting the shorter arm 125 to the longer or tracing arm 126 which terminates in the dressing disk 127 which is attachable to the terminal pin 128. 129 is the fixed point (in the form of a pin carried by the pantograph saddle 32 of the machine) relative to which the pantograph system of levers may be manually moved by means of the handle 130 suitably located on the said tracer arm 126.

The link 124 carries an upstanding tracer mount 131 which supports the tracer 132, in this case a wheel dressing diamond, in such position that upon the operation of the pantograph the said tracer will move in a line directly towards or from the axis of the dresser wheel 26 but in a relation to the plane of the dresser wheel 26 determined by the movement of the dressing disk 127.

With the pantograph proportions taken for this example, the amplitude of movement of the tracer 132 is one-tenth of that of the tracing disk. Therefore, to produce the desired contour dresser by the tracer 132 on the periphery of the dresser wheel 26 I mount, in a pre-determined position on a suitable supporting extension 133 of the saddle 32, a template 134 ten times the size of the form to be ground on the dresser wheel 26. The dressing disk used in that case is also ten times the diameter of the active portion of the tracer diamond 132, and, the dressing

disk 127 and the tracer 132 being both circular so far as their active edges are concerned, the contour of the template will be faithfully reproduced to the required scale by the tracer 132 in dressing the periphery of the dresser wheel 26. In order that a correct setting of the diamond 132 may be readily determined, a location hole 135 is provided in the template 134 to receive the said pin 128 so that the pivot 129, center of diamond 132 and center of the disk 127 may be in alignment when the pantograph elements are set in a neutral relationship as indicated in Figure 8.

The pantograph saddle 32 is adjustable towards and from the dresser wheel 26 by means of the hand screw 33, and is carried by and movable in all directions of adjustment with the dresser wheel motor mounting 29. Thus the tracer 132 may be brought into any desired setting relative to the dresser wheel 26 to properly perform its wheel-dressing function, and readily withdrawn from such setting when its purpose has been accomplished.

As the invention herein described is not limited in its application to the grinding of abrasive wheels for the form finishing of gear teeth forms alone, it is desired that herein and in the claims, the word "gear" shall be deemed to broadly include toothed, lobed and splined forms, even single toothed structures such as shafts having integral keys formed thereon; and that the word "tooth" shall be likewise deemed to include lobes, splines and other surface formations on the work to be form finished.

What I claim is:

1. In combination with a grinding wheel for

the finish forming of gear and other lobed forms, a dresser wheel angularly adjustable and movable relative to the said grinding wheel to form a thread thereon, a pantograph-operated dressing tool for dressing the periphery of said dresser wheel, and a pantograph-guiding template having the enlarged form of the counterpart of the conjugate rack of the work which the grinding wheel is intended to grind, said pantograph-operated dressing tool and said template being swingable with said dresser wheel about an axis passing through the center of said dresser wheel.

2. In combination with a grinding wheel for the finish forming of gear and other lobed forms, a dresser wheel movable relative to said grinding wheel to form a thread on said grinding wheel, a pantograph, a cutter operated by said pantograph for dressing the periphery of said dresser wheel, and an enlarged template formed in counterpart of the conjugate rack of the work to be ground by the grinding wheel, said template guiding said pantograph to effect the dressing of the periphery of said dresser wheel to a contour corresponding to said template whereby said dresser wheel may in turn form a thread on said grinding wheel the cross-sectional form of which thread will be the conjugate rack of the work to be ground thereby, said grinding wheel being adjustably tilttable about a line transverse to its axis, said dresser wheel being adjustably tilttable with and to said grinding wheel about such line, and said pantograph and its template being swingable with said dresser wheel about said line.

WALTER F. ROSS.
